ALTITUDE COMPENSATOR

William A. Marshall, Jr., Oak Park, Ill., assignor
to Stewart-Warner Corporation, Chicago, Ill.,
a corporation of Virginia

Application March 29, 1943, Serial No. 480,974

6 Claims. (Cl. 137—153)

My invention pertains to altitude compensators, and is more particularly concerned with, but not limited to, an altitude compensator for use in aircraft heaters of the internal combustion type.

In the pending application of Lynn A. Williams, Jr., Serial No. 476,429, filed February 19, 1943, there is described an internal combustion type of heater particularly adapted for aircraft, and wherein the fuel supply is controlled by the difference in pressure between the combustion chamber of the heater and the induction tube leading to this combustion chamber. This pressure difference increases with increase in altitude at constant mass flow, and therefore the pressure sensitive device will produce a richer mixture unless some compensating means is provided to offset the effect of the increased pressure drop. Said Williams application discloses and claims the utilization of a pressure responsive means for controlling a vent which prevents this pressure difference from increasing with increases in altitude.

An object of my invention is to provide an altitude compensator which is particularly adapted, but not limited, to use as part of the fuel feeding system of an internal combustion heater like that disclosed in this Williams application.

Another object of my invention is to provide an altitude compensator which is simple, compact, light in weight, and inexpensive to manufacture, but which is sufficiently rugged to give long and trouble-free service.

Another object of my invention is to provide an altitude compensator which may be readily adjusted without disassembly, and in a minimum length of time, with only a simple tool such as a screw driver.

Other objects and advantages will become apparent as the description proceeds.

In the drawings:

Fig. 1 is a view showing my invention applied to an internal combustion type of heater, the heater being shown in longitudinal section;

Fig. 2 is an enlarged sectional view of the fuel feeding control means shown in Fig. 1, and shows, in elevation, my novel compensator applied thereto;

Fig. 3 is an end view of Fig. 2, taken on the line 3—3 of Fig. 2; and

Fig. 4 is an enlarged view showing my altitude compensator in longitudinal section.

In Fig. 1, I have illustrated my invention as used in connection with the fuel feeding system of an internal combustion type of heater. This

heater has a combustion chamber 10 supplied with combustible mixture from an induction pipe 12 communicating with the combustion chamber through slots 14. An electrical igniter 16 serves initially to ignite the combustible mixture supplied to the combustion chamber 10, and is ordinarily provided with a thermostatic switch which disconnects it from its source of electrical current when the heater attains normal operating temperature. A reigniter 18 is provided to insure maintenance of combustion after the igniter 16 has been disconnected from its source of electrical energy.

The hot products of combustion formed in the combustion chamber 10 flow from the right-hand end of this chamber into a tubular heat exchanger 20 of the hollow fin type. The ends of the hollow fins are sealed, as indicated at 22 and 24. A muffler 26 directs the hot products of combustion into the left-hand ends of the hollow fins, and as the hot gases traverse these fins, the heat from the gases is transmitted to the heat exchanger 20. The cooled gases flow from the right-hand ends of the hollow fins into an outlet chamber 28, which communicates with atmosphere through a discharge fitting 30 and any suitable exhaust pipe which may be attached to the threaded end 32 of this fitting.

The muffler 26 has a sheet metal shell 34 provided with openings 36 forming acoustic couplings between the gas passages and the interior of the muffler, which is filled with sound absorbing material 38, such as stainless steel wool or glass wool. The muffler may be provided with a nose 40 forming an empty acoustic chamber 42 connected by openings 44 to the interior of the main part of the muffler.

A fuel jet 46 is located in the induction pipe 12 and is supplied with fuel by a pressure fuel supply means indicated generally by the reference character 48, and connected to the jet 46 by a pipe 50. The fuel supply means 48 operates on the difference in pressure between the combustion chamber 10 and the inlet of a ram 52 which is connected to the pressure device 48 by a pipe 54. Pipe 56 connects the fuel supply means 48 with the combustion chamber 10. A pipe 58 connects the fuel supply means with a fuel pump, elevated tank, or other source of fuel under pressure.

Referring to Fig. 2, it will be seen that communication between the fuel pipe 58 and a chamber 60 is controlled by a valve 62 which is moved to closed position by a lever 64 pivoted on an adjustable support 66. This support may be shifted by an adjusting screw 68 against which the sup-

port is urged by a spring 70. The other end of the lever 64 is pivotally connected to an operating rod 72 attached to a disc 74, closing one end of a bellows 76.

The other end of the bellows 76 is attached to the wall 78 of a casing 80 so that the interior of the bellows 76 constitutes a variable chamber in communication with the ram 52. That part of the casing 80 which is external of the bellows 76 and disc 74, constitutes a second variable chamber 82 which communicates through pipe 56 with the combustion chamber 10. The disc 74 is thus subjected to the differences in pressure between the combustion chamber 10 and ram 52, and this difference in pressure controls the position of the valve 62 and also the pressure in the fluid chamber 60, which extends into the interior of a bellows 84 surrounding the valve operating rod 72. The difference in pressure between the ram 52 and combustion chamber 10 acts over substantially the entire area of the disc 74 and the force thus created acts upon the relatively small cross sectional area of that portion of the fuel chamber 60 which extends into the bellows 84, so that the pressure difference between the ram 52 and combustion chamber is stepped up and acts upon the fuel in the fuel chamber 60 to force this fuel to the jet 46.

The combustion chamber 10 and heat exchanger 20 are surrounded by a cylindrical casing 86 which is connected to an air inlet 88 attached to the usual ram. In the particular heater shown in the drawings, the same ram and inlet provide the combustion air for the induction tube 12. Ventilating air flows between the heat exchanger 20 and casing 86, and picks up heat from the heat exchanger. The heated ventilating air flows from the right-hand end of the casing 86 directly into a cabin or other space to be heated, or into a duct system having outlets at selected locations.

When an airplane provided with such a heater increases its altitude, the pressure drop between the ram 52 and combustion chamber 10 increases for any constant mass flow rate, and this would result in increasing the richness of the mixture supplied to the combustion chamber unless compensating means be provided. This increase in pressure drop can be prevented from affecting the fuel chamber 60 by providing a vent orifice for the interior of the bellows 76 and pressure responsive means for controlling the escape of air through this opening. The subject matter thus far described is claimed in the aforesaid Williams application, and my invention lies in the particular structure of the altitude compensator and associated valve means for regulating the escape of air from the interior of the bellows 76.

Referring more particularly to Fig. 4, it will be seen that I have provided a tube 90 projecting into the interior of the bellows 76, and provided with a longitudinally extending slot 92. A spool shaped valve 94 is slidable in the tube 90 and regulates the escape of air from the interior of the bellows 76 by way of slot 92 and tube 90. In the particular position of the valve 94 shown in the drawings, the valve prevents escape of air from the bellows 76 so that the differential pressure across the disc 74 is the differential pressure between the ram 52 and the combustion chamber 10.

The valve 94 has a valve stem 96 attached to the end 98 of an evacuated bellows 100 supported in a housing 102. The housing 102 is illustrated

as being attached by bolts 104 to the wall 78 of the casing 80.

The housing 102 has an end wall 106 provided with an integral nipple 108 into which a sleeve 110 is threaded engaged. A screw 112 has a smooth end located in the sleeve 110 and a tubular nut 114 located in the sleeve 110, and a flange 116 on the screw 112 is clamped between this nut and sleeve 110 to prevent axial movement of the screw 112, but permitting rotation thereof when a screw driver or similar tool is engaged in the kerf 118 located in the end of the screw.

The threaded end of the screw 112 is located in a threaded tubular support 120 attached to the fixed end wall 122 of the evacuated bellows 100. A pin 124 carried by this end wall is slidably received in the opening 126 formed in a spring support 128 rigidly clamped between the nut 114 and sleeve 110. This pin 124 prevents rotation of the bellows 100 relative to the spring keeper 128 when the screw 112 is rotated to adjust the spring load. A spring 130 is confined between the spring support 128 and a flange 132 of the head 98. This spring tends to expand the bellows 100 and shift valve 94 to permit the escape of air through the slot 92 and tube 90. By rotation of the sleeve 110 the position of the spring keeper 128 can be determined, and thus the setting of the valve 94 can be properly adjusted without dismantling the apparatus.

The bellows 100 is collapsed by the difference in pressure between the interior of the bellows and the space 134 between this bellows and the housing 102. The bellows is shown in collapsed position in Fig. 4, and in this position the head 98 engages the tapered end of the supporting member 120. The space 134 communicates with the interior of the combustion chamber by way of pipes 136 and 56, so that the pressure in the space 134 varies with the pressure in the combustion chamber.

A removable cap 138 is screwed on to the nipple 108 and must be removed to permit adjustment of the screw 112 or sleeve 110. The sleeve 110 is provided at its upper end with a kerf 140 which can be engaged by a screw driver to permit rotation of this sleeve relative to the housing. The device is calibrated in the following manner. A simple adjustment of the screw 112 determines the pressure exerted by the spring 130, inasmuch as rotating this screw in effect lengthens or shortens the bellows 100. Similarly, rotation of the sleeve 110 moves the upper spring keeper upwardly or downwardly without disturbing the position of the bellows relative to the upper spring keeper 128. Therefore, rotation of this sleeve moves the valve 94 inwardly or outwardly without changing the spring pressure.

As the plane carrying the heater rises to higher and higher altitudes, the absolute pressure in the combustion chamber decreases and the absolute pressure in the space 134 likewise decreases. This permits spring 130 to expand bellows 100, thereby moving valve 94 to the left and permitting air to escape from the interior of bellows 76. The leftward movement of valve 94 varies with variations in altitude, and maintains a constant pressure difference across the disc 74 with constant mass flow, and therefore a constant pressure in the fuel chamber 60 for all altitudes. The combustible mixture delivered to the combustion chamber therefore does not increase in richness as the altitude of the plane increases. These advantages are provided by my novel altitude compensator which is simple in construction, light in

weight, inexpensive to manufacture, and sturdy and durable.

It will be appreciated that inward and outward movement of the valve 94 bleeds air from the interior of the bellows 76, thereby altering the pressure difference across the bellows only if the rate of escape of air through the valve 94 is comparatively rapid, inasmuch as air is continuously entering the bellows 76 through the pipe 54. The result is that the flow of air through pipe 56 into the combustion chamber 10 may be more than is desirable, at least in some instances. In order to avoid this comparatively rapid flow of air into the combustion chamber a restriction can be introduced in the line 54 or in the line 56. For purposes of illustration I have shown such an orifice, indicated by the numeral 142, as being located in the fitting which connects the pipe 54 with the interior of the bellows 76, it being understood that this or a similar orifice can be placed in the line 56 instead if desired. The function of the orifice 142 is to restrict the flow of air through the tube 54 to the interior of the bellows 76 so that inward movement of the valve 94 will more readily bring about a pressure drop across the bellows. If the orifice is placed in the line 56, the flow of air through the pipe 54 into the bellows will be comparatively free; thus, regardless of the position of the valve 94 the pressure inside the bellows will remain substantially constant. On the other hand, the suction effect produced exteriorly of the bellows 76 will depend upon the amount of air flowing through the pipe 110 to the orifice located in the line 56. In either case inward or outward movement of the valve 94 effectively controls the pressure drop across the bellows 76 in the manner previously described.

While I have disclosed only a single embodiment of my invention, it is to be understood that my invention is not limited to the details shown and described, but may assume numerous other forms, and that the scope of my invention is defined in the following claims.

I claim:

1. An altitude compensator comprising an evacuated bellows, a casing enclosing said bellows and in spaced relation thereto, a pipe for connecting said space with a variable source of pressure, a tube connecting said space with an adjacent space under pressure, said tube having a longitudinal slot in a wall thereof, a spool-shaped valve movable to control communication between said two spaces by way of said tube and slot, a valve stem connecting said valve with said bellows and a spring for expanding said bellows.

2. Pressure responsive means comprising an evacuated bellows, a housing for said bellows, a screw attaching one end of said bellows to said

housing, a spring confined between said housing and the opposite end of said bellows to expand the same, said screw being adjustable to vary the position between said housing and the first named end of said bellows, means for connecting the interior of said housing with a source of variable pressure, and valve means controlled by said bellows.

3. Compensating means of the class described comprising a fixed support, an evacuated bellows, an adjustable connection between said support and one end of said bellows, a spring for expanding said bellows, said spring being confined between said support and the other end of said bellows, and pressure controlling means connected to said last named end of the bellows and operated by expansion and contraction thereof.

4. An altitude compensator comprising an evacuated bellows exposed to variable external pressure, a support for said bellows, a screw adjustably connecting one end of said bellows to said support, said support having an opening slidably receiving a pin attached to said bellows and serving to prevent rotation of said bellows with said screw, a spring for expanding said bellows, valve means attached to said bellows and controlled by expansion and contraction thereof, said screw being adjustable to vary the pressure of said spring, and a removable cover enclosing said screw.

5. A compensator of the class described comprising an evacuated bellows, a spring for expanding said bellows, a supporting member attached to one end of said bellows, said member having a part engaging the other end of said bellows to limit contraction thereof, a screw engaging said member, a support carrying said screw and bellows, said screw being rotatable to shift the relationship between said support and one end of said bellows, slidable means between said bellows and support to prevent rotation of said bellows with said screw, means interposed between said screw and support to adjust said spring, and pressure control means operated by expansion and contraction of said bellows.

6. An altitude compensator of the class described, comprising a housing, an evacuated bellows located in said housing, an adjustable screw connecting said bellows and housing said screw having a radially projected flange, a sleeve rotatably mounted in said housing and receiving one end of said screw, a tubular nut surrounding said screw and confining said flange between itself and said sleeve, means for expanding said bellows, a support for said last-named means clamped between said nut and sleeve, and pressure control means operated by said bellows.
